(57) **CLAIM**

The ornamental design for a display screen with graphical user interface, as shown and described.

DESCRIPTION

FIG. 1 is a front view of a display screen with graphical user interface showing the design, according to a first embodiment;

FIG. 2 is a front view of a second embodiment thereof; FIG. 3 is a front view of a third embodiment thereof; and, FIG. 4 is a front view of a fourth embodiment thereof. The broken line showing of the display screen and other features form no part of the claimed invention.

1 Claim, 4 Drawing Sheets

FIG. 1

FIG.2

FIG. 3

FIG. 4
